UNITED STATES PATENT OFFICE.

THOMAS O. P. BAILEY, OF PITTSBURG, AND WILMOT G. BAILEY, OF IMPERIAL, PENNSYLVANIA, ASSIGNEES OF ONE-HALF TO MATTHEW H. STEVENSON, OF PITTSBURG, PENNSYLVANIA.

MAIL-BAG CATCHER.

SPECIFICATION forming part of Letters Patent No. 624,444, dated May 9, 1899.

Application filed October 29, 1897. Serial No. 656,777. (No model.)

To all whom it may concern:

Be it known that we, THOMAS O. P. BAILEY, residing at Pittsburg, and WILMOT G. BAILEY, residing at Imperial, in the county of 5 Allegheny and State of Pennsylvania, citizens of the United States, have invented or discovered new and useful Improvements in Mail-Bag Catchers, of which the following is a specification.

10 In the accompanying drawings, which make part of this specification, Figure 1 is a perspective of our improved platform-post, showing the mechanism in position for operation. Fig. 2 is an elevation of our platform-post and mail-car mechanism looking in the direction of the car's travel and showing the device at the moment of the interchange of mail-bags. Fig. 3 is a plan view of the same. Fig. 15 4 is an elevation also of the same at right angles to Fig. 2. Fig. 5 is a side elevation of the platform-post with the arms in their inoperative position. Fig. 6 is a broken elevation of the mechanism carried by the mail-car, and Figs. 7, 8, 9, 10, and 11 are detailed 20 views of the same mechanism.

The purpose of our invention, generally stated, is to provide automatic means for taking up and depositing mail while the train is in motion. The devices in use have as a rule 25 no means for receiving the mail from the train, but it is simply thrown off the car, sometimes falling under the train, resulting oftentimes in the destruction of the mail-matter and occasionally the derailment of the train. There 30 are, however, devices on the market intended to catch the mail from the moving train, but they have so far been experimental and unsatisfactory in operation. Our invention overcomes all these difficulties.

35 The following is a detailed description of our device:

1 is the platform-post, having vertically-pivoted arms 2 and 3. Arm 2 is weighted at its rear end 4, so that it maintains a vertical 40 position when not set for use, as shown in Fig. 5. Arm 2 is provided at its other extremity with a cross-piece 5, which extends beyond the arm 2 at each side and has its ends grooved on top, forming a support for one end of the

mail-bag when the arm is in position. Arm 50 3 is provided at its end with catch 6, which is rotatable to either side, according to the direction in which the train is traveling.

77 are brackets mounted on post 1, between which are pivotally supported catcher-arms 55 8 8. The catcher-arms 8 8 have their unweighted extremities bent in a curve toward the right or left, according to the side of the post on which they are mounted, thus receiving the mail-bag from the moving train without sudden jar, the bend in the arm gradually overcoming the velocity of the bag. Rod 9, passing loosely through eye-lug 9^a on post 1, is provided at its top with beveled portion 10, fitted to force spring-catch 11 on arm 2 out of 60 engagement with catch 11^a on post 1 when rod 9 is forced up. Arm 3 has on its pivoted end projection 12, which when arm 3 falls into the position shown in Fig. 5 strikes against the lower extremity of rod 9, driving said rod 65 up, and by means of beveled portion 10 throwing catch 11 out of engagement with catch 11^a, thus allowing arm 2 to assume its vertical position of rest. Catch 11 and catch 11^a are beveled to insure their easy engagement and disengagement. Catcher-arms 8 8 are weighted 70 at their rear ends 13 13, so their normal position is approximately vertical. When in use, the weighted end of arm 8 is elevated. Pivoted to rod 9 by slotted joints are bent 80 levers 14 14, which operate in recesses cut in post 1 and terminate in catches 15 15, which support arms 8 8 when in position. When rod 9 is forced up, the levers 14 14 turn, releasing the catch 15 supporting catcher-arm 85 8, allowing said catcher-arm to assume its position of rest.

We now pass to that portion of our device which is carried on the mail-car, consisting of a catcher-arm to receive the mail-bag from 90 the platform-post and means for holding the bag which is on the car, so that it may be taken off by the catcher-arm on the platform-post.

On the door-frame of the mail-car 16 are 95 fixed four brackets with perforated lugs 17 17, in which are mounted the rods 18 and 18^a. Mounted to slide on rods 18 and 18^a is upright

19. On the extremities of rod 18 are mounted the coil-springs 18^b to prevent the upright 19 from being thrown against brackets 17 17 when the device is in use. Upright 19 is cut 5 away on both sides near its upper extremity, forming seats 19^a 19^a, so that the catcher-arm and bag-holder may be mounted on either side of upright 19, according to the direction the train travels. Fitted to be held in seat 10 19^a in upright 19 are collars 20 and 21. Passing through said collars 20 and 21 and the ends of seat 19^a is rod 22, fitted at its upper extremity 22^a to engage a wrench or handle. On the bottom of collar 20 is lug 20^a, fitted to 15 move in mortise 21^a in collar 21, so that when collar 20 is revolved it will move a distance equal to the length of the mortise 21^a before projection 20^a strikes collar 21 and causes it to revolve also. Collar 21 is also cut away to 20 form shoulders 21^b and 21^c, which, coming in contact with the sides of seat 19^a, prevent further revolution of collar 21. On the top of collar 20 is beveled gear 20^b, which meshes with vertical double partial gear 22^b, also beveled and mounted in a vertical slot 22^c in upright 19, between seats 19^a 19^a. That portion of upright 19, which separates seats 19^a 19^a and slot 22^c, is partially cut away to permit the meshing of gears 20^b and 22^b. Integral 25 30 with partial gear 22^b is handle 23, which at rest fits into slot 22^c for part of its length. Handle 23 is fitted with spring-catch 23^a, which when the handle is pushed into slot 22^c engages a suitable recess on top of upright 19 and prevents the handle from dropping down 35 from its vertical position. Mounted on collar 20 is arm 24, fitted on its outer end with the double holder 25, the under member thereof consisting of a cross-piece 26, while the upper member is a spring-retainer 27. Member 27 is pivoted at its center to enable the ring on the bag to disengage itself easily therefrom. On the lower face of arm 24 is integral lug 28, on which is horizontally pivoted catch 29, of 40 like construction with holder 25, except that spring member 30 of catch 29 is on the side nearest the collar 20, and said member 29 is pivoted to move slightly in a horizontal plane. 45 29^a is a spring, keeping catch 29 normally 50 at right angles with arm 24. On collar 21 is fixed catcher-arm 31, which is curved, as shown in the figures, so as to gradually lessen the velocity of the bag after it is received from the platform-post. In collar 20 is a set-screw 55 32, so that should any accident render the gears or handle 23 useless set-screw 32 may be screwed into rod 22, and a handle or wrench being applied to the square end 22^a of said rod 22 the collars may thereby be rotated. 60 The portion of our invention carried by the mail-car is so assembled that when the catcher-arm 31 and holder-arm 24 are swung parallel with the side of the car the handle 23 assumes a vertical position in slot 22^c. When handle 65 23 is pulled down, the revolution of partial gear 22^b acts on gear 20^b, revolving collar 20, and with it holder-arm 24. Collar 21 remains 70 stationary until lug 20^a travels the length of mortise 21^a and then striking against the end of said mortise causes collar 21 to turn and 75 with it catcher-arm 31. The turning of these collars would be stopped by shoulder 21^b on collar 21 coming in contact with the side of seat 19^a. To bring the mechanism back to its original position the handle 23 is brought back 80 to its vertical position. This would entail the turning of collar 20 in the reverse direction of that taken above. Lug 20^a would travel back through mortise 21^a until coming in contact with the end thereof it would cause collar 21 to revolve. This turning would continue until the handle 23 assumed a vertical position and shoulder 21^b on collar 21 rested against the side of seat 19^a. The two seats 19^a in upright 19 are of corresponding shape, 85 and the collar 20 is made so that it may be mounted in either seat on rod 22, according to the direction of the train's motion. Collar 21, however, cannot be conveniently made interchangeable on account of the curved form 90 of catcher-arm 31; but two collars having catcher-arms curved in opposite directions must be provided for the device in such cases. The partial gear 22^b has beveled cogs on both faces, so that gear 20^b may mesh in whatever 95 seat 19^a collar 20 is mounted.

The operation of our device is as follows: The mail-clerk on the car would place collar 20 and the proper collar 21 in forward seat 19^a in upright 19. The top of ring 33 on mail-bag 100 34 is slipped in that portion of holder 25 which is to the rear when arm 24 is extended at right angles to the car, and the side of said ring 33 is slipped into the corresponding half of catch 29, which keeps the ring in a vertical plane at 105 right angles to the car when the arm is extended. Handle 23 is then pulled down, turning arm 24 to a position at right angles to the car, and also turning catcher-arm 31 outward to a less extent through the action of lug 20^a 110 in mortise 21^a. The station-master draws down arm 2 and pulls up arm 3, taking ring 33^a at the top of bag 34^a, places the ring over the half of double catch 5, which faces the direction of the train's travel. With the smaller ring 35 at the bottom of bag 34^a he engages 115 catch 6, which he swings around toward the direction of the train's travel. When arm 2 is drawn down, it is held in position by the engagement of catches 11 and 11^a, and 120 the catcher-arm 8 when in position for use is supported by the hook 15 on lever 14, which projects beyond the line of post 1 when rod 9 is at its lowest point. As the train passes the platform-post catcher-arm 8, in position 125 on the platform-post, will engage ring 33 on bag 34, which is held by the catches 25 and 29 on arm 24 on the car and the bag 34 will become disengaged from catches 25 and 29. The gradual curve in catcher-arm 8 will tend 130 to reduce the velocity of bag 34, so that ring 33 will gradually come to a rest on catcher-arm 8 against post 1. Catcher-arm 31 on the car will engage ring 33^a of bag 34^a, held by

arms 2 and 3, and disengage it from catches 5 and 6. The peculiar curve in catcher-arm 31 will take bag 34^a from the arms 2 and 3 with but little jar when the bag reaches the 5 base of the arm. When the bag is snatched from arms 2 and 3, arm 3 in falling, by means of projection 12, strikes rod 9 an upward blow, causing its beveled end 10 to force catch 11 from engagement with catch 11^a, thus releasing 10 arm 2. At the same time the upward movement of rod 9 turns lever 14 slightly, withdrawing hook 15 from under catcher-arm 8, allowing said catcher-arm to assume its position of rest. When catcher-arm 31 on the 15 car receives bag 34^a from the platform-post and catcher-arm 8 on the platform-post receives bag 34 from arm 24, the mail-clerk on the car then pushes handle 23 up into slots 22^a, turning arm 24 and catcher-arm 31 toward the 20 car into their positions of rest. The bag may then be easily slipped off of catcher-arm 31.

While we have described with particularity and detail the various parts, even to the minor portions, of the mechanism, we do not intend to 25 confine ourselves to any subordinate feature or features except where they are expressly set out and enumerated in the claims; but

We intend to claim, broadly—

1. In platform-posts, the combination of an 30 upright; two bag-supporting arms pivoted on said upright; a catcher-arm pivoted on said upright, and means by which the assumption by one of said bag-supporting arms of its inoperative position releases the other bag-supporting arm and said catcher-arm from their 35 operative positions.

2. In platform-posts, the combination of an upright, two bag-supporting arms pivoted on said upright; a catcher-arm pivoted on said 40 upright; a vertically-moving rod carried by said upright and actuated by one of said bag-supporting arms, by means of which rod actuated by said bag-supporting arm the second bag-supporting arm and said catcher-arm are 45 released from their operative positions.

3. In platform-posts, the combination of an upright two bag-supporting arms on said upright; a catch on one of said bag-supporting arms, a second catch on said upright, fitted 50 to engage said first catch when said bag-supporting arm is in operative position, a projection on the other bag-supporting arm; a rod capable of vertical movement fitted to be acted upon by said projection, and capable 55 of disengaging said first catch from said second catch, a bent lever actuated by said rod, and a catcher-arm pivoted to said upright and supported by said bent lever in operative position.

4. In mail-bag exchangers, the combination 60 of an upright carried on the car; a seat in said upright; two collars mounted in said seat, a bag-supporting arm and a catcher-arm attached to said collars respectively; and a rod passing through said collars and the extremities of said seat. 65

5. In mail-bag exchangers, the combination 70 of an upright mounted on the car; a seat in said upright; two collars seated in the said seat, a rod passing through said collars and the ends of said seat; a bag-supporting arm on one of said collars; a lug on the end of said collars; a catcher-arm on the other collar, and a mortise in the end of said collar by which the said lug is engaged. 75

6. In mail-bag exchangers, the combination 80 of an upright mounted on a car; a seat in said upright; two collars seated in said seat; a rod passing through said collars and the ends of said seat; a bag-supporting arm attached to one of said collars; a lug on the end of said collar; a catcher-arm attached to the other collar; a mortise in the end of said collar by which the said lug is engaged; a gear on the other end of said first collar; a vertical gear 85 mounted in said upright and meshing with said first gear, and means for revolving said vertical gear.

7. In mail-bag exchangers, the combination 90 of an upright carried on a car; a seat in said upright; collars mounted in said seat; a bag-supporting arm and a catcher-arm attached to said collars respectively; a rod passing through said seat; having one of its ends fitted to engage a handle or wrench, and means 95 for causing said collars to turn with said rod.

8. In mail-bag exchangers, the combination 100 of an upright mounted on the car; two seats of like reverse elevation in said upright, and collars mountable in said seats; a bag-supporting arm and a catcher-arm attached to said collars respectively.

9. In mail-bag exchangers, the combination 105 of an upright mounted on the car, two seats of like reverse elevation in said upright, two collars mountable in said seats; a catch or arm attached to one of said collars and a bag-supporting arm attached to the second of said collars.

In testimony whereof we have hereunto set 110 our hands this 18th day of March, A. D. 1897.

THOMAS O. P. BAILEY.
